SKI LIFT

Marlyn J. Hauseman, Bozeman, Mont., assignor
to Bridger Ski Lift, Incorporated, Bozeman,
Mont., a corporation of Montana

Application July 26, 1949, Serial No. 106,881

6 Claims. (Cl. 104—112)

1

This invention relates to a towing apparatus and more particularly appertains to a ski tow apparatus for towing skiers up an inclination.

The primary object of this invention is to provide an improved endless conveyor type ski tow lift which can be erected and maintained at a low cost and which will be efficient, safe and reliable in operation.

Another important object of this invention is to tow or pull skiers up a hill at an even and constant rate of speed without imparting any shock to the skier, especially during acceleration of the skier from a standing position to the velocity of the tow.

These and ancillary objects and structural features of merit are attained by this invention, a preferred embodiment of which is set forth in the following description and illustrated in the accompanying drawings, wherein:

Figure 1 is a side elevational view showing the ski tow apparatus in assembled arrangement for towing skiers up a hill;

Figure 2 is an enlarged side elevational view of the driving means for the tow rope or similar member;

Figure 3 is a top plan view of the driving means;

Figure 4 is a fragmentary perspective view of the upper tower assembly of the apparatus, which is anchored at the top of the hill;

Figure 5 is an end elevational view of the lower tower assembly;

Figure 6 is an enlarged elevational view of the carrier member and intermediate guide means for the tow rope;

Figure 7 is a view taken on line 7—7 of Figure 6, looking in the direction of the arrows;

Figure 8 is a top plan view of the guide means;

Figure 9 is a vertical sectional view of the spring box for the carrier member;

Figure 10 is a sectional view taken on line 10—10 of Figure 9;

Figure 11 is a front elevational view of the intermediate tower assembly;

Figure 12 is a side elevational view of the intermediate tower assembly, and

Figure 13 is a side elevational view of the upper tower assembly.

In Figure 1, the ski tow apparatus 10 is illustrated in assembled arrangement for towing skiers up a hill 12 and generally includes an endless or continuous towing rope or similar flexible member 14 from which depends at spaced points carrier members 16. The rope is driven by a drive means 18, which is mounted at the foot 55

2

of the hill or slide and is supported at the top of the hill by a supporting structure 20 with intermediate guide means 22 being provided and disposed along the hill.

5 The drive means 18 and supporting structure therefor includes a base member 24, which is anchored by suitable fastening members to a cement block or other anchoring means, which is embedded in the ground. A pair of uprights 10 or standards 26 and 28 extend upwardly and inwardly relative to each other from the base member. The convergent standards are formed with attaching plates 30 at their lower ends, the plates being pivoted to apertured ears 32 formed integrally on the base member by bolt assemblies 34.

A cap member 36 is provided with downwardly extending integral sleeves or tubular extensions 38 which are disposed on the upper converging ends of the standards. An intermediate standard 40 is provided at its lower end with parallel projecting extensions 42 which are pivotally secured at their lower ends to a complementary pair of apertured ears 44. A cap member 46 is secured on the upper end of the standard 40 and a U-shaped supporting plate 48 is integrally formed on the cap member. A shaft 50 is journaled between the parallel legs of the supporting plate and a bank of pulleys 52 are rotatably disposed on the shaft. A pair of complementary ears 54 extend or project rearwardly from the cap member 36 and a pair of pulleys 56 are journaled on a shaft 58, which is journaled in the ears. A flexible member 59 is trained over the pulleys 52 and 56, the member having one 35 end secured to the cap member 36 and the opposite end secured to a weight 60. Restraining or anchoring cables 62 are secured to an offset section 64 of the cap member 46 and are anchored to the ground by stakes or other means.

40 In this manner, the supporting standards 26 and 28, which support the drive means 18 are tensioned and held in a proper vertical position. Supporting means 66 supports the drive means and includes a U-shaped frame 68 to which is secured, adjacent the web portion thereof, a pair of downwardly extending side bars 70 and 72. A supporting platform 74 extends rearwardly from the lower ends of the side bars 70 and 72 and is disposed in substantial parallelism with the upper forwardly extending U-shaped frame 68. A prime mover 76 is mounted on the platform 74 and a bank of pulleys 78 are fixed on the extending drive shaft 80 thereof. A transversely disposed bar 82 is secured to the web portion of 50 the frame 68 and a parallel transversely disposed

bar 84 is secured between the opposing legs of the frame 68 forwardly of the bar 82. Bearing blocks 86 are secured to the upper faces of the bars and a driven shaft 88 is rotatably disposed therein. A bank of pulleys 90 are secured on the rearwardly extending end of the shaft 88 in vertical alignment with the pulleys 78 and are drivingly connected thereto by means of belts 92.

A housing 94 is supported between the outer ends of the frame 68 and a shaft 96 is vertically disposed therein. A gear 98 is carried by the shaft in intermeshing engagement with a worm 100 fixed on the shaft 88. A drive wheel or pulley 101 is secured on the lower end of the shaft and is rotated through the drive arrangement including the shaft 88 and the gear 98.

A U-shaped flexible guide member 102 embraces a portion of the pulley or drive wheel 101 and is held in a suspended horizontal position from the frame 68 by supporting bars 103. The guide member is formed with outwardly turned unattached ends 104, which project forwardly of the drive wheel. A pair of vertically disposed pulleys 106 and 108 are rotatably carried by stub axles 110 extending laterally from supporting arms 112. The arms 112 are secured to the terminating portions of the opposing legs of the frame 68 and project forwardly and downwardly therefrom in an inclined plane relative to the periphery of the drive wheel.

The pulleys 106 and 108 function to retain the cable 14 in engagement with the drive pulley 101 and to guide the outgoing and return reaches of the cable into contact of the drive pulley.

The guide means 22 includes an intermediately positioned tower structure 114, which includes an angle iron base member 116 on which are integrally formed a pair of complementary apertured ears 118. A tubular supporting member 120 is pivotally secured at its lower end between the ears by a pivot pin 122 and is formed adjacent its upper end with a series of vertically spaced transversely disposed openings 124. A complementary tubular member 126 is slidably disposed in the tubular member 120 and is formed with a series of transversely disposed spaced openings, which are alignable with the openings 124 to receive a pin 128. A pair of rigidifying or bracing bars 130 and 132 are secured to a pair of laterally extending offset sections 134 on the upper end of the tubular member 120 and are pivotally secured at their lower ends to upstanding ears 136 formed integrally on the base member 116. Anchoring cable assemblies 138, of Y-shaped formation, shown in Fig. 11, are provided at each the up-grade and the down-grade sides of the tower structure 114, as shown in Fig. 1, the branches 139 of each cable assembly being secured to the opposing ends of a cross piece 140 which is welded or otherwise secured midway between its ends on the upper end of the tubular member 126. The stems 141 of the cable assemblies 138 are secured to stakes or pegs 142 which are anchored in the ground at an inclined angle away from the vertical plane of the tubular members, with the base member 116 secured by spikes 144 to a concrete block 146 embedded in the ground.

The guide means for the outgoing and return reaches of the cable are supported by the opposing ends of the cross piece 140. In this respect, attention is directed to Figures 6-8. A rod 148 is secured in the opposing ends of the cross piece 140. A supporting bar 150 is transversely secured to the outer end of the rod 148 and a guide

bar 152 is secured parallel to the bar 150 by bolts 154, the bar 152 being spaced from the bar 150 by bushings 156 concentrically disposed on the bolts. The guide bar is formed with inwardly directed opposing ends 158 and 160. The bar functions as a cam bar to space the carrier members 16 from the support bar 150, as the cable is driven and carries the carriers upwardly and downwardly.

10 A pulley 162 is rotatably journaled to the bar 150 in a vertical position below the cable 14. A complementary pulley 164 is resiliently mounted above the pulley 162, so that the cable 14 is guided between the two vertically aligned pulleys. The 15 pulley 164 is rotatably journaled on the outer end of a supporting arm 166 which is pivotally secured as at 168 to an upwardly extending supporting bar 170, the bar being secured at its lower end in an inclined plane to the support bar 150. A rod 172 is formed with a lateral end 174 which is disposed through the supporting bar 150 and is formed with a threaded end upon which is secured a nut 176. The rod extends upwardly and rearwardly from the bar 150.

20 The rod 172 is formed with an externally threaded upper end 178 upon which is secured a nut 180. The rod extends through a vertical opening in the arm 166 and a stop plate 182 is formed integrally thereon with a spring 184 concentrically disposed about the rod and positioned 25 between the stop plate 182 and the nut 180. In this manner, the arm 166 is held under resilient tension, so that the pulley 164 is held in complementary relation with the pulley 162. However, the pulley 164 is allowed to move upwardly 30 and to be spaced from the pulley 162, upon entrance of the attaching means for the carrier units between the two pulleys.

An idler flat pulley 186 is horizontally positioned on a horizontal extension 188, the pulley being rotatably disposed on a vertical shaft 190, so that the periphery thereof is disposed in engagement with the cable 14 for guiding the cable between and retaining the cable in engagement 45 of the two pulleys 162 and 164.

The carrier units include a bead or pressed sleeve 192, which may be in the form of a clamp common in the art, is secured at spaced intervals on the cable 14. A spindle or shaft 194 extends laterally from the bead and is provided 50 with a coaxially reduced end. An arm 196 is formed with a sleeve end 198, which is oscillatably disposed on the reduced end of the shaft 194. The arm 196 is formed at its lower end with an inturned offset extremity 199 to which is pivotally secured by means of a pair of integral apertured ears 200 a spring box 202.

With respect to Figures 9 and 10, it is to be noted that the spring box 202 is formed with a reduced casing 204 which is secured to one side 60 of the box. A shaft 206 is rotatably journaled transversely in the box and casing and a reel 208 is fixed on the shaft. The reel is disposed within the box 202. The reel is formed with a 65 split periphery 210, a transversely disposed pin 212 being positioned in the cut out portion of the hub. A line is secured to the shaft 206, the line being disposed between the pin 212 and the adjacent end of the hub and extending around the hub and outwardly at the bottom or open 70 lower end of the box. A rewind spring structure 216 is disposed within the casing 204 and functions to rotate the shaft 206, so that the take-up line is automatically rewound on the hub. The line is secured at its outer end to an 75

arm 214 formed with an offset apertured lower end 218. The end 218 is slidably disposed on a guide rod 220, which is formed with a laterally disposed apertured end 222 slidably disposed on the shank of the member 214. A recoil spring 224 is disposed about the arm and a rod 226 is formed integrally with the lower end of the member 220 with a seat 228 secured to the lower end of the rod.

Attention is now directed to Figures 4 and 13, wherein the upper tower structure is illustrated in detail. The upper tower structure 20 includes a base member 230, which is preferably an angle iron, having the horizontal portion thereof apertured as at 232 for receiving spikes or similar anchoring means, which are secured to a concrete block 234 anchored in the ground. A pair of upstanding apertured ears 236 are integrally formed on the horizontal portion of the angle iron and tubular uprights or standards 238, 240 and 242 are pivotally secured between the ears, the lower ends of the tubular members being mounted on a common pivot element 244 disposed transversely between the ears. The tubular member 238 is disposed intermediate of the members 240 and 242 and a cap member 246 is secured at the upper end thereof. A cable 248 is secured at one end to the cap 246 and is entrained over a pulley 250 rotatably journaled between a pair of plates 252, which extend integrally from a superstructure 254 pivoted on the upper converging ends of the tubular members 248 and 242.

Anchoring cables 256 extend from the cap 246 and may be anchored in the ground by means of retaining stakes. The opposite end of the cable 248 is secured to a winch (not shown). Thus, it can be seen that the support or upright 238 is held in a desired inclined position by the anchoring cables and the supporting standards 240 and 242 are moved in adjusted vertically swinging positions by means of the cable 248 and a winch or hoisting mechanism.

A pair of parallel supporting bars or plates 257 are integrally formed at one end with the body portion of superstructure 254 and an idler pulley 258 is rotatably carried by the outer ends of the supporting plates and is disposed in a horizontal plane. A U-shaped guide member 260 is suspended from the supporting plates by means of vertical connecting bars 262 and a U-shaped supporting bar 264. A pair of vertically disposed guide sheaves 266 are rotatably mounted on supporting arms 268 which project forwardly from the legs of the U-shaped bar 264.

In operation, the cable is driven by the drive pulley 101, which is operated through the belt transmission system from the prime mover 76. The cable is operatively disposed through the intermediate guide structure and is entrained around the idler pulley 258 on the upper tower structure. The carriers are disposed at spaced points along the cable and suspend therefrom. When a skier sits on one of the seats of the carrier, as seen in Figure 1, the line is unwound on the hub and the shock absorber structure of the rods and spring between the rod 226 and the line absorbs the initial shock. When the skier vacates the seat, the rod 226 and seat move into the position shown in Figure 6 by means of the spring return structure.

The lift may be adjusted to dispose the reaches of the towing rope 14 at the desired distance above the skiing surface of the hill 12, by manipulation of the winch cable 248 (Fig. 13). Thus, by way of example, if it is desired to dispose the

reaches of the towing rope 14 in a lower zone than that shown in Fig. 1 due to a lowered skiing surface resulting from compacting or melting of the snow, the standards 240 and 242 (Figs. 4 and 13) may be allowed to swing toward the standards 26 and 28 (Fig. 5) at the foot of the hill. This results in the standards 26 and 28 swinging in a direction away from the standards 240 and 242, at the top of the hill, the weight 60 becoming lowered during such adjustment and taking up any slack in the flexible member 59. The flexible member 59, in association with bank of pulleys 50 and 56 and the weight 60 also functions to keep the towing rope 14 tensioned throughout this adjustment, and also while the lift is in use.

Of course, since other embodiments and purposes of this invention will become apparent to those skilled in the art, upon a perusal of the foregoing disclosure, in view of the accompanying drawings, it is to be understood that certain changes in size, style and arrangement of parts may be effected thereon, without a departure from the spirit of the invention and within the scope of the appended claims.

Having described the invention, what is claimed as new is:

1. In a ski lift of the class for towing skiers up a hill wherein an endless towing rope is trained about a drive pulley and a driven pulley, and has reaches extending between said pulleys substantially paralleling the inclined surface of the hill; the improvement which comprises: a base member, a pair of standards pivotally connected to said base member and disposed in upwardly converging relation, a first cap member connecting the upper end portions of said standards, an intermediate standard pivotally connected to said base at a zone intermediate the connection of said pair of standards therewith, a second cap member secured to the upper end of said intermediate standard, a bank of pulleys rotatably carried by each said first and second cap members, a flexible member secured at one end portion to said first cap member, extending therefrom toward said intermediate standard and trained about and back and forth between said banks of pulleys with its other end portion trained over one of the pulleys of the bank of pulleys carried by said second cap member, a weight secured to the end of said last mentioned end portion, anchoring cable means connected to said second cap member, disposing said intermediate standard in an inclined position to one side of the plane common to said pair of standards, and supporting and drive means for the drive pulley of the towing rope, carried by the upper portions of said pair of standards.

2. In a ski lift of the class for towing skiers up a hill wherein an endless towing rope is trained about a drive pulley and a driven pulley and has reaches extending between said pulleys substantially paralleling the inclined surface of the hill; the improvement which comprises: a base member, a pair of standards pivotally connected to said base member and disposed in upwardly converging relation, a superstructure pivotally carried at the upper end of said standards, rotatably supporting the driven pulley, an intermediate standard pivotally connected to said base at a zone intermediate the connection of said pair of standards therewith, a cap member secured to the upper end of said intermediate standard, an anchoring cable connected to said cap member, disposing said intermediate stand-

ard in an inclined position to one side of the plane common to said pair of standards and at the side thereof opposite that to which said driven pulley is located, and a winch cable operatively connected to said cap member and superstructure whereby the relative position of said pair of standards may be adjusted with respect to said intermediate standard.

3. In a ski lift of the class for towing skiers up a hill wherein an endless towing rope is trained about a drive pulley and a driven pulley, and has reaches extending between said pulleys substantially paralleling the inclined surface of the hill; the improvement which comprises; a first standard pivoted at its lower portion to swing toward and from the zone of the driven pulley, means carried by the upper portion of said first standard rotatably supporting said drive pulley, a drive means, including a prime mover, operatively connected to the drive pulley, mounted upon the upper portion of said first standard, a second standard pivoted at its lower portion to swing toward and from the zone of said drive pulley, a superstructure mounted upon the upper end portion of said second standard, rotatably supporting the driven pulley, means operatively connected to one of said standards for swinging it about its pivot and retaining it in a set position to space the reaches of the towing rope a predetermined distance above the hill skiing surface, and means operatively connected to the other of said standards for yieldably swinging it about its pivot in a direction to tension the towing rope.

4. In a ski lift of the class for towing skiers up a hill wherein an endless towing rope is trained about a drive pulley and a driven pulley, and has reaches extending between said pulleys substantially paralleling the inclined surface of the hill; the improvement which comprises: a first standard pivoted at its lower portion to swing toward and from the zone of the driven pulley, means carried by the upper portion of said first standard rotatably supporting said drive pulley, a drive means, including a prime mover, operatively connected to the drive pulley, mounted upon the upper portion of said first standard, a second standard pivoted at its lower portion to swing toward and from the zone of said drive pulley, a superstructure mounted upon the upper end portion of said second standard rotatably supporting the driven pulley, means operatively connected to said second standard for swinging it about its pivot and retaining it in a set position to space the reaches of the towing rope a predetermined distance above the hill skiing surface, and means operatively connected to said first standard for yieldably swinging it about its pivot in a direction to tension the towing rope.

5. In a ski lift of the class for towing skiers

up a hill wherein an endless towing rope is trained about a drive pulley and a driven pulley, and has reaches extending between said pulleys substantially paralleling the inclined surface of the hill; the improvement which comprises: a base, a first and a second standard pivotally carried upon said base, means carried by the upper portion of said first standard, supporting the drive pulley of the towing rope to one side of said first standard, tensioning means to the other side of said first standard constructed and arranged to yieldably connect said first and second standards at their upper end portions, and an anchoring cable connected to the upper end portion of said second standard and to the ground, disposing said second standard in upwardly diverging relationship to said first standard, whereby said last mentioned means yieldably tensions the towing rope.

6. In a ski lift of the class for towing skiers up a hill wherein an endless towing rope is trained about a drive pulley and a driven pulley, and has reaches extending between said pulleys substantially paralleling the inclined surface of the hill; the improvement which comprises: a base, a first and a second standard pivotally carried upon said base, means carried by the upper portion of said first standard, supporting the drive pulley of the towing rope to one side of said first standard, tensioning means to the other side of said first standard constructed and arranged to yieldably connect said first and second standards at their upper end portions, an anchoring cable connected to the upper end portion of said second standard and to the ground, disposing said second standard in upwardly diverging relationship to said first standard, whereby said last mentioned means yieldably tensions the towing rope, a prime mover, means carried by said first standard to the side thereof opposite said drive pulley and straddling said tensioning means, supporting said prime mover, and motion transmitting means operatively connecting said prime mover and drive pulley for imparting movement of the former to the latter.
